UNITED STATES PATENT OFFICE.

JOHN JENSEN, OF ROCKFORD, ILLINOIS, ASSIGNOR TO WHITNEY METAL TOOL COMPANY, OF ROCKFORD, ILLINOIS, A CORPORATION OF ILLINOIS.

ANGLE-IRON BENDER.

Application filed April 21, 1924. Serial No. 707,854.

To all whom it may concern:

Be it known that I, JOHN JENSEN, a citizen of the United States, residing in Rockford, in the county of Winnebago and 5 State of Illinois, have invented a certain new and useful Angle-Iron Bender, of which the following is a specification.

The invention pertains to a means for bending angle-iron bars which have been 10 notched or sheared to facilitate the operation of forming a right-angle bend in the bar with a miter joint.

The object of the invention generally stated, is to provide a means of the character indicated whereby the bending operation may be performed effectually and expeditiously.

More specifically stated, one object of the invention is to provide an angle-iron bender 20 having means of an effectual character for clamping the work in position for the bending operation and which is so arranged as not to interfere with the movements of the actuating member.

Another object is to provide an advantageous arrangement for the bending means with respect to the anvil or block upon which the bar is bent.

A further object is to provide a construction which is relatively simple in character and also strong and durable.

In the accompanying drawings,

Figure 1 is a plan view of my improved bender with a notched angle-iron bar clamped in position thereon ready for the bending operation, the lever of the bending means being broken away;

Fig. 2 is an end view of the bender, the work being shown in section;

Fig. 3 is a fragmentary plan view showing the parts in the position which they occupy at the completion of the bending operation; and Fig. 4 is a vertical sectional view taken in the plane of line 4-4 of Fig. 1.

The device comprises a base 7 constructed to provide near its forward edge a seat 8 for a rectangular block 9 so as to support the latter in an elevated position extending transversely of the base. Said block constitutes an anvil over which the bar is shaped to form the right angle bend therein. It may be secured in position upon its seat in any suitable way. 7^a indicates a rest rising from the base, to the right of the

anvil, to assist in supporting the work in position.

The base 7 has a recess 10 in its central rear portion flanked at opposite sides by upstanding flanges 11. In the present instance these flanges are shown as continued at right angles and apertured to receive bolts 12 whereby the base may be secured to any suitable support as for example to a shearing machine or other device for performing some auxiliary operation upon the bar. Between said flanges 11 I mount a vertically disposed lever 13 pivoted to the flanges preferably by means of a trunnion 14 extending throughout the width of the lever which corresponds in width to the distance between the two flanges. Upon the upper end of this lever I provide a clamping member 15 in the form of a block the forward face of which is adapted to engage the rear face of the vertical wall or leg of the angle iron bar placed upon the block or anvil 9. Said clamping member has a pair of rearwardly extending lugs 16 near its opposite ends which are pivotally secured to the upper end 80 of the lever 13 by means of a trunnion 17 extending through the upper end of the lever.

For operating the clamping member 15 I provide a screw 18 threaded in the base below the anvil 9 and extending in a front to rear direction. The forward end of said screw is provided with an operating rod 19 slidably mounted in the head 20 of the screw, and the rear end of the screw extends into the recess 10 between the flanges 11 and engages with the lower end of the lever 13, as will be readily apparent from Fig. 2. It will be observed that the clamping means is so located as to be disposed entirely below and rearwardly of the work 90 so as not to interfere with the operation of the bending means to be presently described.

As above indicated, the angle iron bar to be bent is notched or sheared previously to its insertion in the bending machine to facilitate the formation of the miter joint as is common practice. As shown in Fig. 1, the bar A has a V-shaped notch a in the horizontal wall or leg of the anvil. The bar is so placed that the apex of said notch coincides approximately with the rear corner of the anvil around which the bar is to be bent. Also substantially coinciding with said corner is the fulcrum of the operating or bending lever. In the present in-

stance, this lever comprises a pivoted portion 21, one end of which is mounted upon a bolt 22 which constitutes the fulcrum for the lever. The other end of the lever is 5 constructed to form a socket for receiving the end of an operating rod or handle 23. The bolt 22 may be mounted in the base as shown clearly in Fig. 4.

Pivotedly secured to the portion 21 of the 10 operating lever is a pressure member or shoe 24 of substantially triangular form, the shoe being pivoted at its apex as at 25. The arrangement is such that the heel of the shoe engages with the work adjacent the bending 15 corner of the anvil, and it will be apparent that in the operation of the lever the shoe will maintain a firm seat upon the work. The location of the fulcrum of the lever substantially coincident with the bending corner 20 of the anvil and the apex of the notch in the work renders it possible to perform the bending operation with a minimum expenditure of effort.

It will be seen that I have produced an 25 angle iron bender of a thoroughly practical character. The work may be quickly and easily clamped in position and removed from the machine and the bending operation may be performed easily and effectually to produce a clean sharp bend. Also the work may 30 be firmly held in position and the holding or clamping means is so located as not to interfere in any way with the operation of the actuating lever.

35 I claim as my invention:—

1. An angle iron-bender comprising a base having an upstanding portion providing an anvil, a lever having a clamping member pivoted at one end, said base also having a 40 pair of spaced upright flanges between which said lever is pivotally mounted between its ends, a screw mounted to turn in the base and disposed between said flanges so as to be operable into engagement with 45 the lower end of said lever whereby to move said clamping member toward the anvil to clamp the work therebetween, and a lever pivoted on the base to turn on an upright axis and having a part adapted to engage 50 with the work adjacent one corner of the anvil to bend it around the anvil at such corner.

2. An angle-iron bender comprising in combination a base having an anvil at its

forward edge rising above the base, a lever 55 pivoted between its ends on the base to turn on a horizontal axis spaced rearwardly of said anvil, a clamping member pivoted to the upper end of said lever and adapted to coact with the rear face of the anvil to clamp 60 the work, a screw mounted in the base with its rear end engaging the lower end of said lever and its forward end provided with an operating handle, and a lever pivoted on the base to turn on an upright axis adjacent one 65 corner of the anvil and having a shoe pivoted thereon adapted to engage with the work to bend it around said corner of the anvil.

3. An angle-iron bender comprising a base having a rigid upright block extending longitudinally of the base and adapted to support an angle-iron bar placed on its upper rear corner, a pair of upright supports on the base extending transversely thereof rearwardly of said block and arranged in longitudinally spaced relation, a member entered between said upright supports and pivoted thereto between its ends, a clamping member of substantial length having on its rear face a pair of bearing portions between 80 which the upper end of said member is pivotally secured, means mounted in the base adapted to engage with the lower end of said member to swing it rearwardly and thereby move the clamping member forwardly into engagement with the work on said block, and means mounted on the base near one end of the block adapted operatively to engage with the work to bend it upon the block. 90

4. An angle-iron bender comprising in combination a base having near its forward edge an anvil portion, an upwardly extending lever disposed behind said anvil and pivoted intermediate its ends to said base, a 95 clamping member on the upper end of said lever, a screw mounted in said base and engaging at its rear end with the lower end of said lever, means operable from a point in front of said anvil to turn said screw whereby to bring said clamping member into gripping relation with said anvil, and a bending lever mounted on said base near one end of said anvil. 100

In testimony whereof, I have hereunto affixed my signature.

JOHN JENSEN.
